DESIGN FOR A THERMOSTAT CASING

Benjamin Jarvis Butler, Attleboro, Mass., assignor
to General Plate Company, Attleboro, Mass., a
Corporation of Massachusetts

Application January 12, 1934, Serial No. 50,379

Term of patent 7 years

To all whom it may concern:

Be it known that I, BENJAMIN JARVIS BUTLER, a citizen of the United States and a resident of Attleboro, Bristol County, Massachusetts, have invented a new, original, and ornamental Design for a Thermostat Casing, of which the following is a specification, reference being had to the accompanying drawing, forming part hereof, in which

Fig. 1 is a top plan view of a thermostat casing showing my new design;

Fig. 2 is a front elevation;
Fig. 3 is a bottom plan view; and,
Fig. 4 is a side elevation.

I claim:

The ornamental design for a thermostat casing, substantially as shown.

In testimony whereof, I have signed my name to this specification this 5th day of January, 1934.

BENJAMIN JARVIS BUTLER.
